UNITED STATES PATENT OFFICE.

JULIAN H. RIVERS, OF NEW YORK, N. Y., ASSIGNOR TO UNIVERSAL FIBRE COMPANY, OF NEW YORK, N. Y., A CORPORATION OF DELAWARE.

APPARATUS FOR THE MANUFACTURE OF PULP ARTICLES.

1,367,206.

Specification of Letters Patent.

Patented Feb. 1, 1921.

Original application filed August 15, 1916, Serial No. 114,944. Divided and this application filed May 17, 1918. Serial No. 235,109.

To all whom it may concern:

Be it known that I, JULIAN H. RIVERS, a citizen of the United States, and a resident of the city, county, and State of New York, have invented certain new and useful Improvements in an Apparatus for the Manufacture of Pulp Articles, of which the following, taken in connection with the accompanying drawings, is a specification.

This application, which is a division of my prior application, Serial No. 114,944, for the manufacture of pulp articles, filed August 15, 1916, relates to an apparatus for the manufacture of articles from pulp, for instance paper pulp, and is particularly designed for the production of flat boards and is one which can be more cheaply constructed and operated than those heretofore in use. My invention, which forms the subject matter of this application, is chiefly characterized by the provision of means to simultaneously introduce pressure fluid, on each side of the walls of the hollow mold sections having perforated inner plates, so that the outward pressure on the inner face of the wall is balanced by the inward pressure of a diverted stream of the fluid on the opposite face of the wall.

In the drawings accompanying the application, one example of my invention is shown. Figure 1 is a top plan view partly in section of my device; Fig. 2 is a side elevation of my mechanism, partly in section; Fig. 3 is a front view; Fig. 4 is a diagrammatic elevation showing the principal parts of my mechanism in vertical section, and Fig. 5 is a vertical section illustrating the detail of the construction thereof.

The structure shown in my drawing is adapted to simultaneously produce a plurality of flat pulp boards. It consists of a hollow mold structure provided with hollow side walls having perforated inner plates and constituting lateral sections capable of being moved from a closed position of the device in which the side walls cooperate with the stationary walls to form a hollow chamber, to an open position in which the side walls are brought clear of the other walls, so that the pulp boards formed upon the side walls may be removed therefrom.

The apparatus is supported upon the legs 2 to which the stationary structure consists

ing of the top wall or section 3, the end walls or sections 4 and the bottom walls or sections 5 are secured. Leading into the chamber through the bottom wall thereof is the pulp inlet pipe 6 connected below the valve 7 therein with a pipe leading from a suitable supply of pulp-liquor, such as, for example, the pipe 1 connected with a suitable container (not shown). Below the connection with pipe 1 there is provided a discharge pipe 8 equipped with a valve 9. In the lower part of the bottom section baffles 10 are provided to prevent splashing as the pulp enters. Above these the air and steam pipe 55 perforates the wall 5.

Each of the side sections consists of a hollow wall, comprising an inner, perforated plate 11 and an outer, unperforated plate 12, against which the plate 11 is supported, and from which it is spaced by ribs, shown schematically by the zigzag lines of Fig. 4, which form between them intercommunicating passages through which the pulp-liquor may be led into the discharge apertures 13. These draining walls and passages may be generally similar in construction to those of the barrel mold described in Serial No. 114,944 filed August 15, 1916. Behind or outside of the imperforate plate 12 is a chamber formed between said plate and the dome-shaped plate 14. The periphery of the inner wall of each side section is provided with a rabbet into which for one side section fit the lateral edges of the angle irons 15 fixedly secured to the stationary top and bottom walls of the mold, and for the other side section fit the edges of the laterally floating frame 16, between which and the stationary top, end and bottom walls of the mold a liquid-tight joint is provided by a flexible connection 17, the peripheral edges of which are secured to said top, end and bottom walls and the inner edges of which are secured to said floating frame.

The ends of the side sections are provided with projecting pins 18 upon which hook the lateral latch bars 19 when the mold is closed, which bars are secured to the lateral latch rods 20 which extend vertically and are connected at their upper ends with the top latch rods 21. Secured to the under side of these latch rods 21 are the top latches

22, the hooked ends of which coöperate with the pins 23 carried in the brackets 24 upon the tops of the mold side sections. The lower ends of the lateral latch bars 20 are 5 provided with outwardly projecting pins which extend into suitable terminal slots in the levers 25 (Fig. 2), the opposite ends of which are fixed to the shafts 26 pivotally mounted in the bearings 27 upon the stationary side walls of the bottom section 5 of the mold. These shafts are provided with bottom latches 28 which hook upon the pins 29 carried in the ears 30 projecting downwardly from the side sections.

15 It will be readily understood that by moving upwardly the top latch rods 21 as by means of the cross-bar 31, secured thereto, and the pulley or ratchet lift chain 32, secured to said bar, the top latches 22 will be 20 lifted so as to become unhooked from the pins 23, and the lateral latch bars 20 will also move upwardly and with them the lateral latches 19 so as to unhook the latter from the pins 18. Moreover, the pins on the 25 lower ends of the lateral latch bars 20 will rock the shafts 26 through the intermediary of the levers 25 so as to unhook the bottom latches 28 from the pins 29. The side mold sections are now free so that they can be 30 moved to the open position shown by dotted lines in Fig. 2 by the mechanism now to be described.

At each end of the mold and secured to the stationary end walls 4 thereof horizontally extending tracks 33 strengthened by the braces 34 are provided. Resting upon these tracks are rollers 35 rotatably carried upon pins secured to the blocks 36 secured to the mold side sections; thus the side sections are each capable of being supported 40 by rollers upon the tracks.

At the ends of the mold and supported by the legs 2 are the fluid pressure motors 37 each comprising a cylinder connected by 45 suitable valved connections (not shown). The piston rod 38 of each of the motors 37 is connected by links 39 with the bell crank levers 40 pivotally mounted on the shafts 41 mounted in bearings 42 on the frame 2. 50 The upper ends of the bell crank levers 40 are connected by links 43 with the pins of rollers 35.

The chambers of the side sections formed between the walls 12 and 14 are connected 55 with the interior of the bottom section of the mold by the connection shown enlarged in Fig. 5. This connection comprises the floating pipe 44 passing through an aperture formed in the side wall of the bottom 60 mold section and secured thereto by the diaphragm connection 45. This diaphragm connection comprises a corrugated metallic disk the periphery of which is secured to the interior of said side wall and the central 65 portion of which, apertured for the passage

of the floating pipe 44, is secured to said pipe by a leak-proof joint. The portion of said pipe which extends exteriorly of said side wall is guided within the collar 46 bolted to the outside of said wall and a spring 47 within said collar and between said side wall and the flange 48 on the outer end of said floating pipe tends to thrust said pipe outwardly and to maintain a close connection between the conical valve face on the 75 extremity of said pipe and the coöperating valve face on the inner end of the angle or elbow pipe 49, the outer vertical end of which is connected by the pipe 50 with the interior of said section chamber. Straddling the collar 46 and pivoted thereto is the U-shaped securing member 51 provided with a cam 52 pivoted thereto and equipped with a handle 53. It is obvious that to release the securing member it is only necessary 85 to turn down the handle 53, whereby the cam 52 becomes free of the angle pipe 49 and then moves the thus freed securing member 51 downwardly to the position shown dotted in Fig. 5.

It will be seen that when the side sections have been unlatched and the pipe connection freed, as explained above, and fluid under pressure is admitted to the motors 37, the bell crank levers 40 will be moved to the 95 dotted position of Fig. 2 and the side sections will move laterally, these rollers 35 rolling upon the tracks 33 and the pipe connection elements 49 and 50 withdrawing from the floating pipe 44 until they have 100 assumed the open position shown by the dotted lines in said figure.

In the operation of my invention the pulp is caused to flow into the inlet pipe 1, Fig. 3. From this pipe it enters the bottom mold section through the pipe 6, the valve 7 being open and the valve 9 in the discharge pipe 8 being closed, and encounters the splash-preventing baffles 10, passing by 105 which it enters and fills the mold cavity and begins to deposit upon the perforated plates 11, the pulp-liquor draining through them and discharging through pipe 13. When a sufficient deposit has formed, drying fluid is introduced through the by-pass pipe 55, the drainage pipe valve 9 being 110 opened and later closed.

When the drying operation is completed, the drying fluid pipe is closed and the device 115 is ready for opening to remove the formed boards adhering to the plate 11. This opening operation is accomplished by pulling upwardly the lift chain 32 to unhook the top latches 19, the lateral latches 19 and the bottom latches 28 from their associated pins secured to the mold sections, in the manner 120 already described, and then admitting fluid under pressure into the motors 37. The piston rods 38 of these motors are thus caused to move upwardly to produce a rotation, 125

through the connecting links 39 of the bell crank levers 40 upon their pivots 41, the upper ends of said levers 40 operating through the links 43 to move laterally the pins of the rollers 35 and the mold side sections secured to said pins. In such lateral movement the bottom portions of the side sections are swung outwardly from the stationary parts of the device, the securing members 51 being of course first released by operating the handle 53, as above described, the top portions are swung downwardly and the central sections move horizontally outward being carried by their rollers 35 which run upon the tracks 33. The outermost, or open position of these side sections is shown by dotted lines in Fig. 2. In this position the pulp boards may be removed in any convenient way. It is obvious that to return these sections to closed position, the fluid may be drained from the motors 37 and the side sections swung back into place, and the securing members 51 locked by hand, after which the several latches may be hooked to the appropriate pintles thereon by lowering the pull chain 32.

One of the side sections forms a rabbeted joint with a floating frame 16 (Fig. 4) movable slightly laterally on account of its flexible connection 17 with the stationary walls of the mold cavity. Any tendency of the pressure fluid to free this joint and allow leakage therethrough is overcome by a greater tendency to tighten the joint, this advantageous result being due to the fact that the area of the floating frame 16 and its flexible connection 17 exposed to the pressure medium is greater than so much of the area of the other side of the frame as is exposed to the pressure medium. Whatever the pressure, therefore, the joint is maintained closed. The opposite side section is positively latched to the first mentioned section, and its rabbeted joint with the fixed frame 15 cannot leak, because, while the area against which pressure acts to cause leakage is the area of the side section bounded by the inner edge of said frame 13, the area against which pressure acts to prevent leakage, acting upon this side section through the intermediary of the latches 19, 22 and 28, is the larger area composed of the area of the first section bounded by the floating frame 16 added to the area of the floating frame and its flexible connection 17 exposed to the interior of the mold. It is thus practically impossible for any of the joints to leak.

Differential pressure connections are also provided, between the pipes 50 and the side walls of the bottom section 5 of the flat board machine. The spring 47 normally holds the floating pipe 44 outwardly against the elbow 49. Pressure within these pipes tending to break this joint by moving floating pipes inwardly against such spring pres-

sure has only the area of the floating pipe at this joint to act against and this is overcome, as will readily be seen, by the pressure within the bottom section of the mold acting against the greater area of the flexible dia- 70 phragm 45 to force the floating pipe outwardly and maintain the joint unbroken.

Another important constructional feature of the machine is that which admits the same pressure fluid, which is admitted to the 75 mold cavity, to the chamber in each side section between the retaining plate 14 and plate 12 of the hollow wall. The pressure on one side of the hollow wall is, therefore, counterbalanced by the pressure on the other 80 side of said wall. There is thus no chance for the buckling of said wall and no necessity for massive bracing or other heavy constructions for the purpose of making the mold walls strong enough to withstand the 85 fluid pressure introduced into the mold. When pulp is admitted into the mold cavity through the pipe 6 it is also free to flow through the pipes 44, 49 and 50 into the cavities behind the inner perforated plates of the 90 mold; and when the pulp is withdrawn from the mold cavity through the discharge pipe 8, the pulp in these side cavities is also withdrawn; and when drying fluid is introduced through the pipe 55 into the mold it also 95 enters into these side cavities. Even though air or pulp or other fluid may be trapped within these side cavities when other fluid is admitted to the mold, the result will be the same because the balancing effect is a 100 matter of pressure and not of pressure medium.

Various changes may be made in the structure described without departing from the spirit of my invention as defined in the 105 annexed claims.

I claim:

1. An apparatus for molding pulp articles, comprising a mold having a hollow wall, consisting of an inner perforate plate 110 and an outer imperforate plate, a plate behind the imperforate plate of such wall and with it constituting a closed chamber, and means for simultaneously introducing pulp under pressure into contact with the perforate plate and into said chamber, substantially as and for the purpose described.

2. An apparatus for molding pulp articles, comprising a mold having separable side sections, each side section having a hollow wall consisting of an inner perforate plate and an outer imperforate plate and having also a plate behind the imperforate plate of such wall and with it constituting a closed chamber, and means for simultaneously introducing pulp under pressure into contact with each perforate plate and into each chamber, substantially as and for the purpose described.

3. An apparatus for molding pulp arti- 130

1. A mold comprising a mold having a hollow separable side wall consisting of an inner perforate plate and an outer imperforate plate, a plate behind the imperforate plate of such wall and with it constituting a closed chamber, and by-pass means for introducing pulp under pressure into contact with the perforate plate and into said chamber, substantially as and for the purpose described.
2. An apparatus for molding pulp articles, comprising a mold having pivotally mounted separable hollow side walls, each side wall consisting of an inner perforate plate and an outer imperforate plate and having a plate behind the imperforate plate to form therewith a closed chamber, means for introducing pulp under pressure into contact with the perforate plates of such walls and by-passes connecting with said means and leading one to each such chamber for introducing pulp thereinto, whereby the outward pressure of the pulp on the inner faces of said hollow walls is largely balanced by the pressure of the pulp upon the outer faces of said walls, substantially as and for the purpose described.
3. An apparatus for molding pulp articles, comprising a mold having pivotally mounted separable hollow side walls, each such wall consisting of an inner perforate plate and an outer imperforate plate and having a plate behind the imperforate plate to constitute therewith a closed chamber, means for introducing pulp into contact with the inner faces of such hollow walls, such means including a conduit provided with inwardly projecting baffles, and by-pass pipes connecting with said means and leading to the outer faces of said hollow walls to permit the introduction of a por-

tion of the pulp stream into said chambers to balance the outward pressure of the pulp on the inner faces of such hollow walls, substantially as and for the purpose described. 45

4. An apparatus for molding pulp articles, comprising a mold having separable top, bottom and side sections, said side sections each having a perforate inner plate and, spaced therefrom, an imperforate outer plate and a plate behind the imperforate plate to constitute therewith a closed chamber, means for simultaneously introducing pulp under pressure into contact with the perforate outer plates of said sections and into said chambers, and means for separating said separable sections from each other, substantially as and for the purpose described.

5. An apparatus for molding pulp articles, comprising a mold having separable top, bottom and side sections, said side sections each having a perforate inner plate and, spaced therefrom, an imperforate outer plate and a plate behind the imperforate plate to constitute therewith a closed chamber, means for simultaneously introducing pulp under pressure into contact with the perforate outer plates of said sections and into said chambers, a motor, a lever system connecting said motor with said top section for separating said top section from said side sections, and a connection between said lever system and said side sections operative to separate said side sections from said bottom section after the top section has been separated from the said sections, substantially as and for the purpose described.

In testimony whereof I have hereunto set my hand.

JULIAN H. RIVERS.
